CIRCUIT INTERRUPTER WITH ARC
EXTINGUISHING SHUNTThomas E. Browne, Jr., Pittsburgh, Pa., assignor
to Westinghouse Electric Corporation, East
Pittsburgh, Pa., a corporation of Pennsylvania

Application September 27, 1947, Serial No. 776,513

9 Claims. (Cl. 175—294)

1

This invention relates to power circuit interrupters, in general, and more particularly to improved arc extinguishing structures therefor.

The general object of my invention is to provide an improved arc extinguishing structure in which the power circuit may be interrupted more rapidly and more easily than has been attained heretofore.

Another object is to provide an improved power circuit interrupter having an improved shunting circuit in parallel with the arcing contacts.

Circuit breaker shunts previously proposed or actually used for limiting the rate of rise or ultimate magnitude of voltage restored across the breaker terminals by the circuit at, or just after, the moment of arc extinction have generally consisted of simple resistors and sometimes of simple capacitors. A resistance shunt has the advantage of damping the circuit oscillation and thus limiting the restored voltage magnitude by reducing or eliminating the overswing of voltage above the normal peak value of the circuit voltage which otherwise occurs in slightly damped low-power-factor A.-C., or highly inductive D.-C. circuits. Resistance alone has two principal disadvantages: (a) With it, the maximum rate of voltage recovery occurs initially when rate of dielectric recovery is a minimum in some types of circuit interrupters when opening "short circuits." Resistance shunts are, therefore, comparatively ineffectual in aiding the operation of such interrupters. (b) In order to control the oscillations of high-power circuits, the impedance of the shunt to these oscillating voltages must be fairly low; and such a low impedance, existing also at power frequency (A.-C. circuit) or steady state (D.-C. circuit) for a resistance shunt, results in objectionably large residual current following interruption of the main current. This produces a correspondingly high rate of heating of the resistor and accentuates the difficulty of interrupting the residual current at the final disconnecting break.

Pure capacitance shunts have the advantages of (a) low initial voltage recovery rate and (b) low power-frequency residual currents (zero for a D.-C. circuit) with negligible heating, but they have the serious disadvantage that they diminish the natural damping of the circuit oscillation, thus generally increasing the amplitude of the voltage overswing. When interrupting low-current, highly inductive circuits, capacitance shunts may also accentuate the tendency of such circuits to produce excessively high voltage

2

swings, or "surges," due to premature extinction of the low-current arc before its normal current zero moment (alternating current) or before the current has been sufficiently reduced by the interrupter (direct current).

My invention proposes the use of power circuit interrupter shunts consisting of series-parallel combinations of resistance and capacitance which will enable the circuit to be more easily interrupted and which avoid the above mentioned difficulties with simpler shunts.

Further objects and advantages will readily become apparent upon reading the following specification taken in conjunction with the drawings, in which:

Fig. 1 is a diagrammatic view of a circuit setting forth some of the principles of my invention;

Fig. 2 shows two curves illustrating principles of my invention;

Fig. 3 is a curve of the performance of my improved circuit interrupter;

Fig. 4 is a diagrammatic view of a circuit interrupter embodying my invention and shown in the open circuit position;

Fig. 5 is a diagrammatic view similar to that of Fig. 4, but showing an extended series-parallel network so that the shunt may be effective over a wider range of values of the inductance of the circuit;

Fig. 6 is a side elevational view, partially in vertical section, of a compressed gas type of circuit interrupter embodying my invention and shown in the partially open circuit position;

Fig. 7 is a plan view of the interrupter shown in Fig. 6, but the shunting elements assuming a slightly different form;

Fig. 8 is a plan view of the circuit interrupter of Fig. 6 with the shunting elements assuming a still further modified form;

Fig. 9 is a side elevational view of a liquid-poor single bushing type of circuit interrupter embodying my invention;

Fig. 10 is an enlarged fragmentary vertical sectional view through the interrupter of Fig. 9, the contacts being shown in the open circuit position;

Fig. 11 is a fragmentary sectional view taken along the line XI—XI through the explosion chamber shown in Fig. 10;

Fig. 12 is a sectional view taken substantially along the line XII—XII of Fig. 10, looking in the direction of the arrows; and

Fig. 13 is a sectional view similar to that of Fig. 12 taken through a modified type of circuit

interrupter of the type shown in Fig. 10, but employing the shunting elements in a different arrangement.

Referring to the drawings, and more particularly to Fig. 1 thereof, it will be noted that there is shown a generator of voltage E furnishing power to a circuit of inductance L and having a circuit interrupter in which an arc X is established. The arc X is shunted by a condenser C and a resistance R . The voltage across the arc terminals is designated by e .

It may be readily shown by standard methods of circuit analysis that the differential equation for the arc terminal voltage, e , of Fig. 1 following a momentary extinction of the arc is

$$\frac{d^2e}{dt^2} + \frac{1}{RC} \frac{de}{dt} + \frac{e}{LC} = \frac{E}{LC} \quad (1)$$

where E is the steady-state or the peak voltage of the generator (in the A.-C. case, E is assumed to be constant during the time considered). The "complementary function" solution of this equation can be written

$$e_c = A_1 e^{m_1 t} + A_2 e^{m_2 t} \quad (2)$$

where the m 's are determined by the quadratic equation

$$m^2 + \frac{1}{RC} m + \frac{1}{LC} = 0 \quad (3)$$

giving

$$m = -\frac{1}{2RC} \pm \sqrt{\frac{1}{4R^2C^2} - \frac{1}{LC}} \quad (4)$$

If the expression under the radical in (4) is a positive quantity, m is real and (2) has the form of an exponential relation. If the expression under the radical in (4) is negative, however, m is a complex number which yields a trigonometric (sine and cosine or oscillatory) type of solution for Equation 2 with an exponential damping coefficient. Clearly, the border line condition occurs when the radical has the value zero, for which

$$\frac{1}{4R^2C^2} = \frac{1}{LC} \quad (5)$$

or

$$R = \frac{1}{2} \sqrt{\frac{L}{C}} = R_s \quad (5')$$

With this "critical" relation between R , L and C , the complementary function becomes

$$e_c = e^{-\frac{t}{2RC}} (A + Bt) \quad (6)$$

as shown in texts on differential equations.

By standard methods, the "particular integral" of Equation 1 turns out to be merely

$$e_p = E \quad (7)$$

giving the complete solution in general form for the case of critical damping:

$$e = e_c + e_p = e^{-\frac{t}{2RC}} (A + Bt) + E \quad (8)$$

The arbitrary constants, A and B , can be evaluated from the initial conditions:

$$e = E_a \text{ and } \frac{de}{dt} = \frac{I_1}{C} \text{ at } t = 0$$

where E_a is the arc voltage and I_1 is the arc current at which the arc suddenly fails, or "goes out," initiating the voltage transient being con-

sidered. This evaluation yields the complete voltage rise equation:

$$e = E - e^{-\frac{t}{2RC}} \left[E - E_a + (E - E_a - 2RI_1) \frac{t}{2RC} \right] \quad (9)$$

Assuming both E_a and I_1 to be zero (approximating the A.-C. case) and substituting τ for the relaxation time, $2RC$, leads to the per-unit form of (9):

$$\frac{e}{E} = 1 - e^{-\frac{t}{\tau}} - \frac{t}{\tau} e^{-\frac{t}{\tau}} \quad (10)$$

Equation 10 is plotted as curve 1 of Fig. 2 of the drawings.

It is to be noted that the correspondingly simplified equation for the voltage oscillation with such a circuit undamped,

$$\frac{e}{E} = 1 - \cos \frac{t}{\tau}$$

has been plotted as curve 2 in Fig. 2 for purposes of comparison. The ordinate value 1 indicates the steady-state or the peak value of the generated voltage in Fig. 2.

Fig. 4 shows a circuit interrupter 3 having a pair of arcing contacts 4, 5 and a pair of disconnecting contacts 6, 7. The contact 4 is relatively stationary and cooperates with the movable arcing contact 5 to establish an arc indicated by the dotted line 8. The disconnecting contacts 6, 7 are separated only after interruption of the arc 8. They then function to break the residual current arc designated by the reference numeral 8a.

During the closing operation, the operating coil 9 is energized by suitable means (not shown), to move the armature 10 upwardly as shown in Fig. 4, at first to cause engagement between the disconnecting contacts 6, 7 and subsequently to cause reengagement of the arcing contacts 4, 5 thereby to complete the circuit through the load 11. The load 11 has an inductance L . There is also a small inductance L_0 associated with the generator E and the supply leads.

It will be noted that I have provided a shunting circuit about the contacts 4, 7 including a capacitance C_1 . The capacitance C_1 is shunted by an impedance branch including a resistance R and a capacitance C_2 . Here, the capacitance C_1 serves to reduce the natural oscillation frequency of the circuit and especially the initial voltage recovery rate. If, in the parallel branch, C_2 is considerably larger than C_1 , its impedance at the oscillating frequency will be small compared to R and so this branch will have a high power factor at this frequency and will serve as an effective damping means to limit the maximum value of the restored voltage appearing across the arc terminals 4, 5. The damping will be especially effective if R is of the order of the value of

$$R_C = \frac{1}{2} \sqrt{\frac{L}{C_1}}$$

required for critical damping of the L , C , circuit alone. The inductance L_0 of the supply circuit is neglected, attention being paid only to the inductance L of the load 11.

This circuit does not yield to mathematical analysis so simply as does that of Figure 1, but an oscillographic study of such a circuit in which load currents are interrupted shows the characteristic voltage recovery 12 to be as shown in Fig. 3, where E is the peak generated voltage. Here, the initial voltage recovery rate, as indicated at 13, is zero, and the maximum recovery rate is

principally determined by C_1 (for a given value of L). With R equal to R_c , the overswing ratio

$$\frac{e_m}{E}$$

can be made as small as one pleases by indefinitely increasing the ratio of C_2 to C_1 . For limited values of

$$\frac{C_2}{C_1}$$

e_m has been found to be a minimum for R slightly larger than R_c .

In case a fault, as indicated by the short circuit 14 occurs across the load 11 necessitating an opening of the circuit interrupter 3, the supply circuit inductance L_0 in combination with C , would require a critical damping resistance R_c smaller than that determined for the much larger load inductance L , thus apparently leaving this circuit with relatively little damping. Experience has shown, however, that normal circuit losses plus residual conductance of the arc path provide effective damping for this small inductance "short" circuit even without a shunting resistor. Under this condition, also, the capacitor C_1 is especially effective in promoting instability of the arc and so in aiding interruption of the short-circuit.

As indicated, a limitation of the shunting combination of Fig. 4 is that its maximum damping effect occurs at the value of load inductance L for which it has been adjusted and, with changing loads, becomes less (may permit higher peak voltages, e_m) for values of L very much larger or smaller than this. For extension of the effectiveness of such a shunt over a wider range of values of L , the damping branch RC_2 can be replaced by a multi-section repeated series-parallel network such as that illustrated in Fig. 5. Such a network, being a type of low-pass filter, can be designed to vary its effective resistance and series capacitance values in such a way as substantially to compensate for changes in oscillation frequency due to changes in L . The circuit of Fig. 5 was found (with

$$R_1=R_2=R_3=R_4 \text{ and } C_2=C_3=C_4=C_5=2.5 \text{ } C_1$$

to give satisfactory damping for variations in L by a factor of 100 or more. A different relation between successive resistance and capacitance values in the damping network might give more efficient utilization of the circuit elements.

With the foregoing principles in mind, I shall now describe some applications of my invention as applied to high voltage circuit interrupters of both the compressed gas form and the liquid break form. Referring to Fig. 6, the reference numeral 16 designates a grounded base upon which is mounted a high voltage compressed air form of circuit interrupter generally designated by the reference character 17, and including an interrupting chamber 18 serially connected with disconnect contact structure 19, the latter being shown in the closed position. The chamber 18 is formed by a cylinder 20 preferably formed of a vitreous insulating material. Interiorly of the chamber 18 is a movable contact 21 separable downwardly away from a stationary orifice shaped contact 22 to draw an arc 23. Suitable means, not shown, may be provided to admit compressed gas from a source of compressed fluid upwardly through the supporting column 24 and adjacent the arc 23 as indicated by the arrows 25.

The gas passes out of the interrupter 17 through the hollow stationary contact 22.

A bracket 27 of plate-like configuration juts laterally from a casting 28 which fastens the 5 supporting column 24 and the vitreous cylinder 20 together. The bracket 27 supports the shunting circuit including the condenser C_1 and C_2 . The upper end of the condenser C_1 is connected electrically to the stationary contact 22 by a conducting strap 29. In parallel with the condenser C_1 is the parallel impedance branch including the condenser C_2 and the resistance R . Preferably, the resistance R assumes the form of a tube 30, the composition of which is such as to provide the 10 15 desired resistance.

Following extinction of the arc 23, the disconnect contact structure 19 is operated to cause opening of the movable disconnect contact 31 upwardly to the position shown in dotted lines 32. 20 Thus there is a considerable gap provided between the movable disconnect contact 32 and the stationary disconnect contact 33, the latter connecting with the line terminal 34. The other line terminal 35 of the circuit interrupter 25 30 35 40 45 17 is electrically connected to the stationary contact 22. It will be noted that the arcing contacts 22, 21 of the circuit interrupter 17 have in parallel therewith a shunting circuit such as shown in Figure 4, and the theory of operation is 30 the same as that previously described in connection with Fig. 4.

Referring now to Fig. 7, it will be observed that I have shown a plan view of a circuit interrupter of the type described in Fig. 6 with the exception 35 that the impedance branch which parallels the capacitance C_1 (which in Fig. 6 includes the elements R and C_2) in Fig. 7 consists of five parallel branches symmetrically positioned about the capacitance C_1 . Each of these five parallel 40 45 branches around C_1 has $1/5$ the admittance of the parallel branch R and C_2 of Fig. 6. Thus, the electrical effect is the same and the only difference is a different form of shunting path about the capacitance C_1 . The interrupting chamber 18 and the disconnect contact structure 19 is the same as was described in Fig. 6.

Referring to Fig. 8, it will be noted that I have shown a circuit interrupter of the type set forth in Figs. 6 and 7, but the shunting circuit about the capacitance C_1 assumes the form as set forth in Fig. 5, where the damping branch RC_2 is replaced by a multi-section repeated series-parallel network such as that illustrated in Fig. 5. The theory of operation is the same as that described 55 in connection with Fig. 5.

Fig. 9 designates a liquid-poor single bushing type of circuit interrupter, designated by the reference numeral 31. Certain constructional features thereof are set forth in United States 60 65 70 patent application filed May 19, 1945, Serial No. 594,634, now Patent No. 2,479,381, by Leon R. Ludwig and Benjamin P. Baker and assigned to the assignee of the instant application.

It will be noted that a base 38 supports a 70 75 80 grounded framework 39 at the upper end of which is supported a circuit interrupter of the single bushing type. Fig. 10 shows more clearly the internal construction of the interrupter. Referring to Fig. 10, it will be observed that the grounded framework 40 supports a single terminal bushing 41 at the lower end of which is secured an arcing chamber generally designated by the reference numeral 42. A stationary contact 43 is disposed at the upper end of the arcing chamber 42.

Cooperable with the stationary contact 43 is a movable contact 44 shown in the open circuit position in Fig. 10. A compression spring 45 biases the contact 44 downwardly in the circuit opening direction. A movable disconnect contact 46 makes abutting engagement with the lower end 47 of the movable contact 44 during the closing stroke, to carry the latter upwardly against the biasing action exerted by the compression spring 45 until the movable contact 44 makes abutting engagement with the stationary contact 43. The movable disconnect contact 46 is rod-shaped in configuration and is guided by upstanding brackets 48. The brackets 48 are mounted adjacent the lower end 49 of the cylindrically shaped housing structure 50.

Fig. 11 shows the internal structure of the arcing chamber 42. It will be noted that a slot 51 is provided longitudinally of the arc 52 which is established by the contacts 43, 44. Arc extinguishing liquid, such as circuit breaker oil 53, fills the housing 50 to the level 54, as shown in Fig. 10. Thus, the establishment of an arc 52 between the contacts 43, 44 within the explosion chamber 42 during the opening operation established pressure therein to cause a blast of fluid laterally of the arc 52 and out of the arcing chamber 42 through the lateral slot 51. The arc 52 is hence interrupted by a turbulent blast of oil out of the arcing chamber 42.

Fig. 12 is a fragmentary plan sectional view through Fig. 10 to indicate the shunting circuit arrangement utilized in Fig. 10. It will be noted that a connector 55 electrically connects the stationary contact 43 with the capacitance C_1 . Shunting the capacitance C_1 are four parallel impedance branches collectively forming electrically a single impedance branch paralleling the capacitance C_1 . Each of the other capacitances 56 has a capacitance value of

$$\frac{C_2}{4}$$

and the resistance tubes 57 have a resistance value of $4R$. In other words, the shunting circuit assumes the same form electrically as that shown in Fig. 4. The use of four capacitances collectively totalling a value equal to C_2 simplifies the mounting arrangement and permits their symmetrical mounting around one half of the periphery of the arcing chamber 42 on a support plate 58, the latter secured by one or more bolts 59 to the lower end of the extinguishing chamber 42. A strap connector 60 electrically connects the support plate 58 to the movable contact 44.

Fig. 13 is a view similar to Fig. 12, but shows a modified type of shunting arrangement which assumes the form of that already described in connection with Fig. 5. In other words, Fig. 13 shows the interrupter of Fig. 10 with the exception that the damping branch RC_2 is replaced by a multi-section repeated series-parallel network such as that illustrated in Fig. 5.

Actual interruption tests with an air-blast circuit interrupter shunted by two condensers and a resistor connected as in Figure 4 have demonstrated the effectiveness of such a shunt in substantially reducing the air pressure required for interruption over a 40 to 1 range of current-limiting inductances. Tests were made at 50 to 4,000 amperes at 13,300 and 6,900 volts, 60 cycles. The shunt was adjusted for an inductance value near the maximum since it was found, as mentioned above, that unavoidable losses in the practical test circuit alone caused sufficient damping

at the lower inductance values to prevent large voltage overswings.

These shunts combine the desirable characteristics: (a) Low residual steady-state or power frequency currents and losses, (b) minimum rate of voltage rise initially, (c) small voltage overswing, (d) possibility of automatic adjustment for a wide range of circuit conditions, (e) applicability to either A.-C. or D.-C. circuit interrupters.

Although I have shown and described specific structures, it is to be clearly understood that the same were merely for the purpose of illustration and that changes and modifications may readily be made therein by those skilled in the art without departing from the spirit and scope of the appended claims.

I claim as my invention:

1. A circuit interrupter including means establishing an arc, a capacitor connected directly in parallel with said means, and an impedance branch shunting the capacitor including a serially related resistance and a capacitor of greater capacitance than the first said capacitor.

2. Arc extinguishing means including contact means for establishing an arc, a capacitor connected directly in shunt with the contact means, and a shunting impedance branch also across the contact means including a serially related resistor and a capacitor of greater capacitance than the first-mentioned capacitor.

3. Circuit interrupting means for interrupting a load having an inductance L including contact means for establishing an arc, a capacitance C_1 connected directly in parallel with the contact means, an impedance branch including a resistor R and a serially related capacitance C_2 having a higher value capacitance than the first said capacitance in shunt with the capacitance C_1 , the resistor R having a value of the order of magnitude of

$$\frac{1}{2}\sqrt{\frac{L}{C_1}}$$

4. A circuit interrupter including means establishing an arc, a capacitor connected directly in parallel with said means, an impedance branch shunting the capacitor including a serially related resistance and a capacitance having a greater capacitance than the first said capacitor, and means for interrupting the residual current through the interrupter.

5. Arc extinguishing means including contact means for establishing an arc, a capacitor connected directly in shunt with the contact means, a shunting impedance branch also across the contact means including a serially related resistor and a capacitor having a greater capacitance than the first-mentioned capacitor, and means for interrupting the residual current through the arc extinguishing means.

6. A circuit breaker including a pair of separable arcing contacts, a capacitor connected directly in shunt with the arcing contacts, a plurality of cascade connected impedance branches in shunt with the capacitor, and each impedance branch including a serially related resistor and capacitor shunting the preceding capacitor.

7. A circuit breaker including a pair of separable arcing contacts and a serially related pair of separable disconnect contacts, a capacitor connected directly in shunt with the arcing contacts, a plurality of cascade connected impedance branches in shunt with the capacitor, each impedance branch including a serially related resistor and capacitor shunting the preceding

capacitor, and the disconnect contacts opening after the arcing contacts to interrupt the residual current through the circuit breaker.

8. A circuit interrupter including an arcing chamber, means for establishing an arc within the arcing chamber, means for subjecting the arc to a blast of fluid to facilitate its extinction, a capacitor connected directly in parallel with the arc, an impedance branch shunting the capacitor including a serially related resistance and a capacitance having a greater capacitance than the first said capacitor, and disconnect means for interrupting the residual current arc through the capacitor and shunting impedance branch.

9. A circuit interrupter of the fluid blast type including an arcing chamber, means for establishing an arc within the arcing chamber, means for subjecting the arc to a blast of fluid to facilitate its extinction, a capacitor connected directly in parallel with the arc, a plurality of cascade connected impedance branches in shunt with the capacitor, each impedance branch including a serially related resistor and capacitor shunting

10
the preceding capacitor, and disconnect means for interrupting the residual current.
